UNITED STATES PATENT OFFICE

119,662

DESIGN FOR A SHOE HEEL

Frank W. Warner, Jr., Pittsfield, Mass., and
Arthur C. Trecece, Chicago, Ill., assigners to
General Electric Company, a corporation of
New York

Application December 3, 1938, Serial No. 81,536

Term of patent 14 years

To all whom it may concern:

Be it known that we, Frank W. Warner, Jr., and Arthur C. Trecece, citizens of the United States, residing respectively at Pittsfield, in the county of Berkshire, State of Massachusetts, and at Chicago, in the county of Cook, State of Illinois, have invented a new, original, and ornamental Design for a Shoe Heel, of which the following is a specification, reference being had to the accompanying drawing, forming a part thereof, and wherein Figs. 1 and 2 are side and rear

views, respectively, and Fig. 3 is a perspective view, of a shoe heel showing our new design.

The characteristic features of our design reside in a translucent heel having a series of vertical holes therein of varying depth, as shown.

We claim:

The ornamental design for a shoe heel, as shown and described.

FRANK W. WARNER, JR.
ARTHUR C. TREECE.
